Patented June 28, 1960

188,305

SLIP FIT WALL FLANGE OR THE LIKE

John H. Hosking, Cincinnati, Ohio, assignor to John H. Hosking Co., Cincinnati, Ohio, a corporation of Ohio

Filed Apr. 21, 1959, Ser. No. 55,599

Term of patent 14 years

(Cl. D91—1)

Fig. 1

Fig. 2

Fig. 3

Fig. 4

Fig. 5

Fig. 1 is an elevational view of the front of a slip fit wall flange showing my new design.

Fig. 2 is an elevational view of the left side of the flange as shown in Fig. 1.

Figs. 3 and 4 are top and bottom plane views, respectively, of the flange shown in Fig. 1.

Fig. 5 is an elevational view of the rear of the flange shown in Fig. 1.

I claim:

The ornamental design for a slip fit wall flange or the like, as shown.
